UNITED STATES PATENT OFFICE.

SAMUEL LIPPINCOTT GRISWOLD KNOX, OF MILWAUKEE, WISCONSIN,
ASSIGNOR TO THE BUCYRUS COMPANY, OF SOUTH MILWAUKEE,
WISCONSIN, A CORPORATION OF WISCONSIN.

TRAVERSING MECHANISM.

No. 811,230.

Specification of Letters Patent.

Patented Jan. 30, 1906.

Application filed April 24, 1905. Serial No. 257,164.

To all whom it may concern:

Be it known that I, SAMUEL LIPPINCOTT GRISWOLD KNOX, a citizen of the United States, residing in Milwaukee, county of Milwaukee, Wisconsin, have invented certain new and useful Improvements in Traversing Mechanism; and I do hereby declare the following to be a full, clear, and exact description of the invention, such as will enable others skilled in the art to which it appertains to make and use the same.

The invention relates to apparatus for traversing or transporting excavators or other heavy wheeled machines from place to place, and has for its object to provide mechanism that may be attached to a machine of the general character noted, so that the latter may carry its own track, which is first engaged by the traction-wheels of the machine and then moved forward a given distance in regular alternation, so that the entire mechanism is advanced in any desired direction with comparative rapidity.

To this end the invention comprises a movable track-section, upon which the machine advances, means for lifting the machine from the track-section at intervals, and means for alternately advancing the track-section and the lifting means as they are relieved of the weight of the machine.

In the accompanying drawings, Figure 1 is a plan view showing the tracks of a machine-car with the invention applied thereto. Fig. 2 is a side elevation of the car and the traversing mechanism. Fig. 3 is a transverse sectional elevation thereof.

Referring to the drawings, A indicates the car body or support upon which the excavating or other machinery is mounted, said car-body being supported by the usual traction-wheels H, upon which the machine is moved from place to place. Coöoperating with the car-wheels H is a movable track-section, somewhat longer than the wheel-base of the car, consisting of rails M M, mounted upon sleepers N N and connected together by rods or ties O O. In order to permit the track-section to take the curves in a roadway or to pass around obstructions, it is provided with adjustable means for varying its direction, which means consist of turnbuckles and draw-rods P, interposed between the ends of the rails on each side of the track-section, so that by ad-

justing the turnbuckles the direction of the track-section may be varied at will from straight parallelism to any desired degree of curvature.

Attached by bolts or other suitable means to the side beams of the car are depending brackets or castings B, two on each side of the car adjacent to the trucks. Each of these brackets carries at its lower end a large roller C and two smaller rollers D. The rollers C coöperate with inclines E E on the shoes or skids G G, which lie parallel with the track-section, and rollers D D, which are adapted to engage yokes or straps F F, which are also connected to the skids or shoes G G and overlie the inclines E E. When the shoes or skids G G are not resting on the ground, they hang on and are supported by rollers D D under the straps or yokes F F.

On one of the axles of the wheels H (which are propelled in the usual way from the sprocket-wheel J) is mounted a drum K, which carries two ropes L L', leading off in either direction and attached at their ends to the cross rods or ties O O of the tracks M M.

The traversing action of the machine is as follows: From the engine or other prime mover of the machine on the car the latter is propelled along the tracks M M for several feet by means of the sprocket J and its operative connection with the car-axles. The rope L assures no slipping of the wheels. The rollers D D, working under the straps F F, tend to lift the shoes or skids G G from the ground, and thereby drag them along with the car. The engine is then reversed, and as the car starts backward the rollers C C ride up the inclines E E, forcing the shoes or skids against the ground and lifting the car and its trucks clear of the tracks M M. The rope L assumes the strain incident to hoisting the car up the inclines E E after the car-wheels have left the tracks, and as the rope L is attached to the track-section and the latter is relieved of the weight of car the friction of the track against the ground is inadequate to hold the rope. Therefore the track-section is slid forward to an advanced position. The engine is again reversed, the car first rolls down the inclines E E and then forward on the rails M M, and the operation repeated.

It will be noted that the car rides up the inclines E E just far enough to clear the wheels

H H from engagement with the tracks and until the latter are relieved of the weight of the car. Hence the backward movement of the car is relatively small.

5. While the turnbuckles P are well adapted to adjust the rails to steer the course of advance in any direction, it is to be understood that other means for changing the direction of the rails may be employed as within the scope 10 of the invention.

What I claim is—

1. Apparatus for traversing or transporting excavators or other heavy machinery, comprising a movable track-section upon which 15 the machine is mounted, means for lifting the machine from the track-section at intervals, and means for alternately advancing the track-section and the lifting means as they are relieved of the weight of the machine.

20. 2. Apparatus for traversing or transporting excavators or other heavy machinery, comprising a movable track-section upon which the machine is mounted, means movably connected with the machine for lifting the same from the 25 track-section at intervals, and means for advancing the track-section when the latter is relieved of the weight of the machine.

3. Apparatus for traversing or transporting excavators or other heavy machinery, comprising a movable track-section upon which the machine is mounted, means movably connected with the machine for lifting the same from the track-section at intervals, and power mechanism on the machine for advancing the movable track-section when the latter is relieved 35 from the weight of the machine.

4. Apparatus for traversing or transporting excavators or other heavy machinery, comprising a movable track-section upon which the 40 machine advances, an auxiliary supporting-section for lifting the machine from the main track, and means for successively advancing the respective sections as they are relieved of the weight of the machine.

45. 5. Apparatus for traversing or transporting excavators or other heavy machinery, comprising a movable track-section upon which the machine advances, an auxiliary supporting-section connected to the machine and having 50 inclines for lifting the machine from the main track-section and means for successively advancing the respective sections as they are relieved of the weight of the machine.

6. Apparatus for traversing or transporting 55 excavators or other heavy machinery, comprising a movable track-section upon which the

machine advances, an auxiliary section having inclines thereon, brackets connecting the machine and the auxiliary section and coöperating with the inclines to lift the machine from 60 the main track-section, and means for successively advancing the respective sections as they are relieved of the weight of the machine.

7. Apparatus for traversing or transporting excavators or other heavy machinery, comprising a movable track-section upon which the machine advances, an auxiliary section comprising skids having inclines and supporting yokes thereon, brackets on the machine having rollers coöperating with the inclines and 70 yokes to lift the machine and advance the skids respectively, and means operated by power mechanism on the machine for advancing the main track-section as the latter is relieved of the weight of the car.

8. Apparatus for traversing or transporting excavators or other heavy machinery, comprising a movable track-section upon which the machine advances, an auxiliary section comprising skids having inclines and supporting yokes thereon, brackets on the machine having rollers coöperating with the inclines and yokes to lift the machine and advance the skids respectively, a drum on the axle of the machine, a cable wound on the drum and connected at its ends to opposite points on the main track-section, and power mechanism on the machine for driving said axle.

9. In mechanism for traversing or transporting excavators or other heavy machinery, a 90 movable track-section, and means connected therewith for varying the direction of the advance of said track-section.

10. In mechanism for traversing or transporting excavators or other heavy machinery, 95 a movable track-section, and adjustable members in the rails of said track-section for varying the direction of advance of the respective rails from straight parallelism to any desired degree of curvature.

11. In mechanism for traversing or transporting excavators or other heavy machinery, a movable track-section, and turnbuckles interposed between the rails of said track-section for varying the direction of the latter.

In testimony whereof I affix my signature in presence of two witnesses.

SAMUEL LIPPINCOTT GRISWOLD KNOX.
